SET OF PLAYING PIECES

James Hsu, Great Neck, N. Y.

Application August 23, 1950, Serial No. 11,892

Term of patent 14 years

(Cl. D34—5)

To all whom it may concern:

Be it known that I, James Hsu, a citizen of the Republic of China, residing at Great Neck, in the county of Nassau and State of New York, have invented a new, original, and ornamental Design for a Set of Playing Pieces, of which the following is a specification, reference being had to the accompanying drawing, forming a part hereof, wherein:

Fig. 1 is a front elevational view of the set of playing pieces, showing my new design;

Fig. 2 is a vertical-sectional view of the set of playing pieces, taken along the dot-dash lines indicated in Fig. 1;

Fig. 3 is a top view of a representative piece; and

Fig. 4 is a side view of a representative piece.

I claim:

The ornamental design for a set of playing pieces, as shown.

JAMES HSU.
